Dec 833.

Samuel F. Pratt, of Boston, Mass

Assignor to

Treadwell, Perry and Norton of Albany, N.Y.

Letters Patent No. 833, Dated Sept. 23. 1856

The schedule referred to in these Letters Patent, and making part of the same.

Be it known, that I, S. F. Pratt, of the City of Boston, County of Suffolk, and State of Massachusetts, have produced a new and original ornamental design, for the plates of a Parlor Stove, called by me the Cuban Stove, and I hereby declare that the annexed drawings are accurate delineations of the said plates and their ornamental parts, (with the exception of the back plate not delineated). The end plates not shew in the drawing, being symmetrically similar to the plates shew, and the half of all the plates not shew, being also symmetrically similar to the parts shew in the drawings.

What I claim as my production and desire to secure by Letters Patent, is the combination and arrangement of ornamental figures and forms, represented in the accompanying drawing forming together the ornamental designs for the plates of a parlor stove.

Signed at Boston, County of Suffolk, State of Massachusetts, this twenty fourth day of July, A. D. 1856
